UNITED STATES PATENT OFFICE

2,617,511

TYPEWRITER CARRIAGE AND BEARING
THEREFOR

Giuseppe Prezioso, Yverdon, Switzerland, assignor to Paillard S. A., Sainte-Croix, Vaud, Switzerland, a corporation of Switzerland

Application June 8, 1949, Serial No. 97,819
In Switzerland June 25, 1948

3 Claims. (Cl. 197—60)

1

In known constructions of typewriters, the carriage rolls on two rolling rails generally arranged in a plane which is horizontal or is inclined relatively to the base of the machine. In all these constructions, the ball bearings located on the rails, not only have to support the weight of the carriage, but also the forces due to the fact that the latter is not balanced relatively to the rails. On the other hand, in the majority of known constructions, at least one of the rails is located behind the platen of the carriage, which renders difficult the mounting and accessibility of the members carried by the framework of the typewriter and which control the movements of the carriage.

The present invention has for its object, amongst other things, to remedy these disadvantages by a particular arrangement of the rolling rails for the carriage. According to the invention these are located underneath the platen in a vertical plane passing substantially through the centre of gravity of the carriage.

One form of construction of the subject of the invention is shown by way of example in the accompanying drawing, wherein:

Fig. 1 is a view showing diagrammatically the arrangement of the carriage on the machine.

Fig. 2 is a diagrammatic view in perspective, to a larger scale, with parts in section.

Fig. 3 is a cross section of the carriage.

With reference to the drawing, it will be seen in Figs. 1 and 3, that the carriage 1 is mounted on two rolling rails 2, located underneath the platen 3, in a vertical plane passing substantially through the centre of gravity of the carriage.

The rolling rails 2 are secured to the body 4 of the carriage located in a vertical plane and which is formed by a single part. The rails 2 are disposed one above the other so as to form a recess adapted to co-operate with a rail 5 secured to the front vertical edges of the upwardly opening slots 6a of the framework 6 of the typewriter. Between the rail 5 and the rails 2 are located rolling balls 7.

The arrangement is such that the vertical plane passing through the centre of the balls 7 passes substantially through the centre of gravity of the carriage 1, that is to say the weight formed on the one hand by the platen 3 and the members for feeding the paper, and the lever actuating the carriage is substantially equal to that formed, on the other hand, by the body 4 of the carriage and the members located on its rear portion such as margin stops 9 and tabulator members 10, and consequently substantially balance one another.

As a result the forces acting on the rails 2 are substantially limited to the weight of the carriage which is supported by the upper rolling track, the lower rolling track serving only as a guide.

60

2

As will be seen in Fig. 2, the plates 11 forming the ends of the carriage and which serve to support the platen and the other members of the carriage are formed by sheet metal parts, secured on edge, for example by screws, to the body 4. The upper portion of the latter is beveled and serves as a support for a guide 12 for the introduction of the sheet.

As will be seen in Fig. 1, the construction above described enables the covering of the carriage to be attached in a harmonious manner to the rear part of the typewriter. Further it will be seen that the carriage may be actuated absolutely freely by the user without his hand meeting any obstacle whatsoever.

I claim:

1. A typewriter carriage including a platen, comprising, a vertically disposed body having in one of its longitudinal sides a horizontally extending recess for receiving a rail affixed to the framework of the machine, said body having a supporting top surface rearwardly of the platen, a sheet feeding guide supported by the top surface rearwardly of the platen and a platen supporting plate at each longitudinal end of the body.

2. The carriage according to claim 1 and wherein the top surface of the body is an inclined plane supporting the sheet feeding guide, and the longitudinal ends of the body carrying the platen supporting plates are plane surfaces perpendicular to the vertical plane of the body.

3. In a typewriter, a pair of side frames each having upwardly opening slots, a rail having forwardly extending portions secured to the frame at the front vertical edges of said slots, a carriage body comprising a vertical portion having spaced guides on its front side cooperating with the rail to slidably mount the carriage, said portion having an upwardly and rearwardly inclined supporting face, platen supporting plates at the ends of said vertical portion of the body and extending forwardly and rearwardly thereof, a platen mounted in said plates, and a sheet feeding plate extending between said plates and resting on the said inclined supporting face of the vertical portion of the body to be disposed tangentially to the lower peripheral portion of the platen.
